E. R. BELL,
SELF LOCKING ADJUSTABLE SHORE,
APPLICATION FILED JAN. 17, 1917.

1,273,811.

Patented July 30, 1918.

UNITED STATES PATENT OFFICE.

EARL R. BELL, OF COVINGTON, KENTUCKY, ASSIGNOR OF ONE-HALF TO JOSEPH NEYER, JR., OF CINCINNATI, OHIO.

SELF-LOCKING ADJUSTABLE SHORE.

1,273,811.

Specification of Letters Patent. Patented July 30, 1918.

Application filed January 17, 1917. Serial No. 142,851.

To all whom it may concern:

Be it known that I, EARL R. BELL, a citizen of the United States, residing at Covington, in the county of Kenton and State 5 of Kentucky, have invented certain new and useful Improvements in Self-Locking Adjustable Shores; and I do hereby declare the following to be a full, clear, and exact description of the invention, such as will enable others skilled in the art to which it 10 appertains to make and use the same.

This invention relates to improvements in adjustable shores.

The object of this invention is the provision of an adjustable shore which may be adjusted to various lengths without injury to the material of which the strut or shore is composed and is so constructed as to automatically lock itself in its adjusted position.

20 A still further object of this invention is the provision of a base, a pair of spaced uprights secured to the base, adjustable member slidably mounted between the standards and means arranged between the side 25 members or standards for automatically holding and locking the adjusting member.

A still further object of this invention is the provision of a self locking adjustable shore of this character which will be simple, 30 practical and comparatively inexpensive in construction and one that can be manufactured and sold at a low cost.

With these and other objects in view the invention consists in the novel combination 35 and arrangement of parts hereinafter more fully described and set forth in the claims hereto appended.

In the drawing—

Figure 1 is a front elevation of my improved self locking shore as made in accordance with this invention,

Fig. 2 is a longitudinal sectional view of the same, and

Fig. 3 is a transverse sectional view taken 45 on the line 3—3 of Fig. 1.

Like numerals of references designate corresponding parts and all the figures of the drawing.

50 Referring more particularly to the drawing the numeral 1 designates a rectangular base which may be constructed of wood, metal or any other material suitable for the purpose.

Secured to the upper side of the base and 55 extending vertically therefrom is a pair of

spaced standards 2 which standards have connected to their upper ends a spacing block and cap 3, which cap has a depending central portion on its under side 4 which is located between the upper ends into engagement with the opposing sides of the standards 2. The cap 3 and spacing block 4 are secured to the upper ends of the standards in any suitable manner suitable for the purpose. 60

A metal supporting strap 5 has secured transversely across the rear faces of the standards 2 adjacent the upper ends thereof and rigidly supports the standards in spaced relation to one another. 65

A second reinforcing strap 6 is secured to the front faces of the standards and is arranged transversely thereacross and co-operates with the strap 5 in holding the standards against separation or collapsing inwardly or outwardly when assembled. 70

A substantially rectangular sliding block 7 is located between the standards 2 and is provided centrally on its upper face with the retaining lug 8, the purpose of which 75 will be hereinafter more fully described.

Removably secured to the front and rear faces of the supporting block 7 are the straps 9 which are secured thereto by suitable fastening means 9^a which straps have their ends 80 extended beyond the side members 2 and bent angularly as at 10^a to engage the outer side faces of the standards 2 and constitute guides permitting the upward and downward sliding movement of the supporting 85 block 7.

A supporting tube or pipe 10 is slidably arranged through the cap 3 and spacing block 4 centrally thereof and has its inner end removably fitted about the lug 8 of the 90 supporting block 7 as clearly shown in Fig. 2 of the drawing. The upper end of said supporting tube or pipe 10 is provided with screwthreads 11 on which is secured a cap 12 which is adapted to engage an obstacle 100 to be supported when the device is in use.

A pair of substantially rectangular metal clutch plates 13 are each provided with central openings 14 and slidably arranged about the tube. The clutch plates 13 are each arranged between or located between the standards 2 and have one end resting upon the reinforcing straps 5 and 6 and are arranged in superposed relation as clearly shown in Fig. 2 of the drawing and when in clutch 110

operating position are inclined as clearly shown in Fig. 2 thus holding the supporting tube or pipe 10 in either raised or any of its adjusted positions.

- 5 It being understood that when it is desired to release or permit the supporting tube or pipe 10 to be lifted upwardly or let down it is only necessary to raise the clutch plates 13 to horizontal positions as shown at 10 15 in dotted lines and the tube is automatically released and permitted to go downwardly or outwardly as desired.

In the assembling of the device and use:

- 15 The standards are arranged upon the upper side of the base 1 and the cap is positioned at the upper ends thereof, the straps 5 and 6 are secured to the standards, the supporting block is arranged or located between the standards 2, side straps are positioned around the standards 2 and are removably secured to the supporting block, the tube is arranged vertically through the cap and spacing block and has its inner end or lower end removably secured to the supporting block. Clutch plates are arranged between the standards 2 and one of their edges resting upon the upper longitudinal edge of the reinforcing straps 5 and 6 and the tube is extended through the opening 14 in these 30 plates.

- When it is desired to raise the tube to varied or adjusted positions it is only necessary to apply a pressure on the underside of the cap 12 and lift upwardly thus pulling the tube or pipe 10 out to the required length and by releasing this pressure the plates drop to an inclined position thus automatically locking the tube in its adjusted position.

When it is desired to release the tube or pipe it is only necessary to raise the clutch plates 13 to a horizontal position thus permitting the tube or pipe to be moved inwardly which will be clearly understood by referring to the drawings. 45

What is claimed is:

A self locking shore of the class set forth including a rectangular base, a pair of spaced standards secured to and rising vertically from the upper side of the base, a spacing block and cap secured to and connecting the upper ends of the standards, a tube slidably arranged between the standards and centrally through the spacing block or cap, a cap on the upper end of the tube, a supporting block located between the standards and removably secured to the lower inner end of the tube, guides carried by the block and engaging the sides of the standards to prevent it from shifting laterally during upward and downward movement, blocks secured to the opposite sides of the standards, a fish plate surrounding the tube having one edge resting upon the upper edges of the straps to hold the tube in its adjusted position when moved within the standard. 55 60 65

In testimony whereof I affix my signature in presence of two witnesses.

EARL R. BELL.
